UNITED STATES PATENT OFFICE.

PETER A. GOODWIN, OF OWENSBOROUGH, KENTUCKY.

FURNACE.

SPECIFICATION forming part of Letters Patent No. 431,458, dated July 1, 1890.

Application filed May 21, 1889. Renewed February 7, 1890. Serial No. 339,514. (No model.)

To all whom it may concern:

Be it known that I, PETER A. GOODWIN, a citizen of the United States, residing at Owensborough, in the county of Daviess and State 5 of Kentucky, have invented certain new and useful Improvements in Furnaces for Steam-Boilers; and I do hereby declare that the following is a full, clear, and exact description of the invention, such as will enable others skilled in the art to which it appertains to make and use the same.

My invention relates to furnaces for steam-boilers or other purposes.

The object of my invention is to secure 15 complete combustion of the fuel.

It is well known that in furnaces having forced or induced draft through the fire-chamber a large per cent. of the gaseous products of combustion pass off unconsumed and are 20 therefore wasted. This is due in part to the irregular quantity and improper condition of the air introduced. Good results have been attained by the introduction of air at the proper place in properly-regulated quantities 25 and at the proper temperature; and my invention consists in improved means for heating air, regulating the amount to be used, and to secure its introduction at the proper point to insure complete combustion.

30 In the drawings forming a part of this specification, Figure 1 is a plan of a boiler and a section through the boiler-furnace on the line $x x$ of Fig. 3. Fig. 2 is a longitudinal section through the furnace on the line $z z$ of Fig. 3. Fig. 3 is a transverse section through the furnace on the line $y y$ of Figs. 1 and 2, the boiler 35 being shown in elevation; and Fig. 4 is an elevation of a coil or system of pipes suitable for use in the heater-boxes or the bridge-wall.

40 A is an ordinary boiler, and B is the brick-work of a furnace therefor. Within the side walls of the furnace I arrange preliminary heating-coils or systems of pipes C C. These coils are provided with valves $c c$, through 45 the medium of which the admission of cold air is regulated. The coils or pipes communicate with heater-boxes D D, arranged abreast of the lower part of the boiler and forming the inner wall of the furnace. The 50 heater-boxes communicate with a chamber E in the bridge-wall of the furnace by means of pipe-connections $d d$. They also are pro-

vided with lateral nipples or perforations d' d' for discharging air across the furnace just in front of and near the bridge-wall. The 55 chamber E in the bridge-wall is also provided with perforations or nipples $e e$ for discharging air into the furnace at the bridge-wall, where it unites with and consumes the escaping gases resulting from imperfect combustion. There may be arranged in the heater-boxes and in the chamber in the bridge-wall coils or systems of pipes, as shown in Fig. 4, or of any desired form and construction, or either of these may be dispensed with and a 60 coil alone substituted therefor.

In operation, the valves being open, air is admitted to the preliminary heating-coils C C in the walls of the furnace, and, becoming heated, passes onto the boxes D D to be further heated, and is thence discharged in part through pipes $d d$ to the chamber E, where the heat is further augmented, and thence through perforations $e e$ at the bridge-wall. Simultaneously air is discharged laterally 75 across the furnace in front of the bridge-wall through nipples or perforations $d' d'$. The perforations through the walls of chamber E may be horizontally forward and backward vertically and at all angles between to mix 80 the heated air with the escaping gases.

The invention described is simple and easily applied. It secures as complete combustion and prevents waste as well as the most elaborate and complicated contrivance hitherto devised. According to my plan any number of boilers may be set up side by side and all 85 equally supplied with hot air to enhance combustion. The lateral discharge of air from the heater-boxes D D, in connection with the 90 discharge in all directions from the chamber in the bridge-wall, produces such counter-currents as to secure a most perfect commingling of air with the products of imperfect combustion.

Having now described my invention, what I claim is—

1. In an air-feeding furnace for steam-boilers, the combination of preliminary heating-coils arranged in the side walls, heating boxes 100 or coils connected with said heating-coils arranged abreast of the boiler and forming the inner wall of the furnace, and a chamber or coil in the bridge-wall communicating with

said heating-boxes provided with perforations for discharging hot air at the bridge-wall, substantially as described.

2. In an air-feeding furnace for steam-boilers, the combination of preliminary heating-coils arranged in the side walls, heating boxes or coils connected with said heating-coils arranged abreast of the boiler, and a chamber or coil in the bridge-wall, the chamber and the heating-boxes being perforated, as described, to discharge counter-currents of heated air about the bridge-wall, substantially as described.

3. The combination, in a furnace, of valved

preliminary heating-coils, heating-boxes 15 abreast the boiler, and a chamber in the bridge-wall communicating with each other, the chamber and the heating-boxes being provided with openings to discharge counter-currents about the bridge-wall of the furnace, 20 substantially as described.

In testimony whereof I affix my signature in presence of two witnesses.

PETER A. GOODWIN.
